(57) **CLAIM**

The ornamental design for a left hand handlebar controller for an all terrain vehicle, as shown and described.

DESCRIPTION

FIG. 1 is a perspective view of a left hand handlebar controller for an all terrain vehicle showing our design;

FIG. 2 is a front elevational view thereof;

FIG. 3 is a back elevational view thereof;

FIG. 4 is a top plan view thereof;

FIG. 5 is a bottom plan view thereof;

FIG. 6 is a bottom perspective view thereof;

FIG. 7 is another bottom perspective view thereof;

FIG. 8 is a right side elevational view thereof; and,

FIG. 9 is a left side elevational view thereof.

The portions shown in broken lines form no part of the claimed design.
